UNITED STATES PATENT OFFICE.

SIMON J. HARDING, OF HARRISBURG, PENNSYLVANIA.

WASHING-MACHINE.

1,190,404.

Specification of Letters Patent.

Patented July 11, 1916.

Application filed January 22, 1916. Serial No. 73,681.

To all whom it may concern:

Be it known that I, SIMON J. HARDING, a citizen of the United States, residing at Harrisburg, in the county of Dauphin and State of Pennsylvania, have invented new and useful Improvements in Washing Machines, of which the following is a specification.

This invention relates to washing machines, and it has particular reference to machines of that type in which a frame adapted to be mounted in position for operation on an ordinary wash tub is utilized to support a rubbing board, a vibratory frame carrying a roller that coöperates with the rubbing board, and a pump or plunger which derives motion from the vibratory frame, said pump being utilized to project water on the clothes or fabric that is being subjected to the conjoint action of the rubbing board and the roller.

One object of the present invention is to produce a shield or deflector whereby the stream of water projected by the pump will be prevented from splashing on the floor or over the sides of the device, said shield or deflector being hingedly supported and vibrated by the action of the vibratory frame so that when said frame carrying the roller is projected forwardly out of engagement with the rubbing board the shield or deflector will be moved out of the path thereof.

A further object of the invention is to utilize the hingedly supported shield or deflector as a supporting means for a distributing box or receptacle whereby soap in powder form may be applied to the fabric that is being washed.

A further object of the invention is to simplify and improve the general construction and arrangement of parts constituting the improved device.

With these and other ends in view which will readily appear as the nature of the invention is better understood, the same consists in the improved construction and novel arrangement and combination of parts which will be hereinafter fully described and particularly pointed out in the claims.

50 In the accompanying drawing has been illustrated a simple and preferred form of the invention, it being, however, understood

that no limitation is necessarily made to the precise structural details therein exhibited, but that changes, alterations and modifications within the scope of the claims may be resorted to when desired.

In the drawing, Figure 1 is a top plan view of a device constructed in accordance with the invention. Fig. 2 is a longitudinal vertical sectional view taken on the line 2—2 in Fig. 1. Fig. 3 is a sectional detail view showing the shield or deflector raised. Fig. 4 is a detail view in side elevation, showing the upper extremities of the uprights of the main frame and showing also the upper portion of the rocking frame connected therewith.

Corresponding parts in the several figures are denoted by like characters of reference.

The frame of the improved machine is adapted to be supported on an ordinary wash tub, and said frame includes side members 15 and front and rear members 16, 17. The front member 16 supports a pump barrel 18 which may be of rectangular cross section, said barrel being provided at its upper end with a closure 19 through which operates the stem 20 of a piston or plunger 21. From the upper end of the barrel 18 a spout which may consist simply of a slot 22 extends through the front member 16. A narrow shelf 22' is arranged below the spout or slot 22. In operation, the lower end of the pump barrel extends within the tub, and water raised by the plunger will be projected through the spout 22 in a forward direction.

The side members 15 of the frame support the rubbing board 23, and said side members are provided with uprights 24 connected together at their upper ends by a cap piece 25. The uprights 24 are provided with slots 26 for the reception of trunnions 27 at the ends of the top cross piece 28 of a rocking frame, the side members of which, 29, afford bearings for the journals of a roller 30 which is preferably corrugated, as shown, and which is adapted to coöperate with the rubbing board 23. Springs 31 are arranged to force the roller carrying frame resiliently in the direction of the rubbing board, said springs permitting the roller carrying frame to rise so as to accommodate light or

heavy material. The roller carrying frame has a handle 32 whereby it may be manipulated, and the side members 15 of the frame are provided with stops 33 to limit the rocking movement of the frame in a rearward direction. The parts are so proportioned that the rocking roller carrying frame may be swung in a forward direction clear of the rubbing board so that the operator may 10 readily reach in front of said rubbing board into the tub for the purpose of adjusting the fabrics that are to be washed upon the rubbing board.

Hingedly connected with the top edge of 15 the front member 16 of the frame is a shield 34 which may be partly supported on the top edges of the side members 15. The top cross bar 28 of the rocking frame has a forwardly extending arm 35 which is initially utilized 20 for the purpose of actuating the plunger of the pump, said arm being bifurcated at its forward end to form prongs 36, each of which is provided with a horizontal slot 37. The plunger stem 20 extends upwardly between the prongs 36, and said stem is provided with a cross piece 38 having rollers 39 that engage the slots 37. Thus, the plunger will be actuated by the rocking movement of the roller carrying frame. The shield 34 is 25 connected with the arm 35 by a flexible element, such as a chain 40. The flexible element 40 is so proportioned that when the roller 30 carried by the rocking frame is at the rearward limit of its movement, the said 30 flexible element will be slack, as seen in Fig. 2, thus permitting the frame carrying the rubbing roller to be rocked within certain 35 limits with the roller in engagement with the board 23 without tensioning the chain or 40 affecting the position of the shield 34. It is only when the roller is moved in a forward direction beyond a certain limit that the flexible element becomes tensioned and the shield lifted thereby, as seen in dotted lines 45 in Fig. 2. Thus, when the roller carrying frame is rocked in a forward direction, the shield will be lifted or swung about its 50 hinges into the position seen in Fig. 3.

Supported on the underside of the shield 55 is a box or receptacle 41 having sifting apertures 42 in the side wall thereof that faces the front member 16 of the frame and which, when the shield is raised, is presented in a downwardly inclined direction. 60 The box 41 is utilized as a receptacle for soap powder which, when the shield is lifted, will be sprinkled through the apertures 42 upon the shelf 22' from which, by the stream of water coming through the slot or spout 22, it will be distributed on the garments or fabric that is being moved from the bottom of the tub and upon the rubbing board, the soap powder being thus sprinkled upon that 65 part of the garments which is due to be next

operated upon between the rubbing board and the roller. Owing, however, to the fact that the shield is not actuated until the roller approaches the forward limit of its movement, there will be no needless use or waste of the soap powder contained in the receptacle 70 associated with the shield.

From the foregoing description, taken in connection with the drawing hereto annexed, it will be seen that I have produced a very simple and improved washing machine or 75 device by the use of which a stream of water may be projected on the garments that are being washed, soap powder being also delivered upon the garments and a shield being provided whereby splashing is prevented, 80 said shield being hinged so that it will be moved out of the path of the rocking roller carrying frame.

Having thus described the invention, what is claimed as new, is:—

1. In a device of the class described, a frame having side members and front and rear members, a rubbing board extending between the side members, a pump depending from the front member and having a spout 90 whereby water is directed toward the rubbing board, a pump plunger, a rocking frame connected with the pump plunger to actuate the same and having a roller to engage the rubbing board, a shield hinged to the front member of the frame, and a flexible connection between the shield and the rocking frame, said flexible connection having sufficient slack to enable the rocking frame to be 95 operated within predetermined limits without affecting the position of the shield.

2. In a device of the class described, a frame having side members and front and rear members, a rubbing board extending between the side members, a pump depending from the front member and having a spout whereby water is directed toward the rubbing board, a pump plunger, a rocking frame connected with the pump plunger to actuate the same and having a roller to engage the rubbing board, a shield hinged to the front member of the frame, and a flexible connection between the shield and the rocking frame, said flexible connection having sufficient slack to enable the rocking frame to be 100 operated within predetermined limits without affecting the position of the shield.

3. In a device of the class described, a 105 main frame having side, front and rear members, a rubbing board supported between the side members, a rocking frame supporting a corrugated roller that cooperates with the rubbing board, a pump including a 110 plunger and a spout for projecting water within the frame, a hinged shield to prevent water from splashing over the frame, and 115

means connecting the pump plunger and the shield with the rocking roller carrying frame to be actuated thereby, in combination with a sifting box supported on the underside of the shield and having an apertured wall arranged to face downwardly when the shield is elevated.

In testimony whereof I affix my signature in presence of two witnesses.

SIMON J. HARDING.
